WINDOW CURTAIN AND DRAPERY FIXTURE

Filed May 1, 1946

member 24 engaged in said end. Another member 25 of the extensible rod is slidable in the bore of the elliptical portion 21 of the tubular member and shown to be of corresponding tubular elliptical shape in cross section and of less cross sectional dimension than the bore of the elliptical portion 21, as shown in Figure 6. To prevent binding of the member 25 in the elliptical portion 21 and limit the outward movement of the member 25, the elliptical portion 21 is arranged with a shoulder 26 adjacent the free end thereof and extending inwardly into the bore thereof to slidably engage and support the member 25, and said free end of the elliptical portion 21 is flanged inwardly to also slidably engage and support the member 25, as shown at 27 in Figure 6. The inner end of the member 25 is flared, as at 28 in Figure 6, to slidably engage the wall of the bore of the elliptical portion 21 and abut the shoulder 26 in the outward movement of the member 25. The member 25 is slidably supported at three spaced points in the elliptical portion 21 by the shoulder 26, the flanged end 27 and the flared end 28. The inward movement of the member 25 in the elliptical portion 21 is limited by the flared end 28 abutting the juncture between the elliptical and circular portions 21 and 22.

The members 21 and 25 may be of circular shape in cross section and in said formation the inward movement of the member 25 in the member 21 will be limited by the flared end 28 abutting the pin 23.

To position the arms 21-28 in horizontal alignment with each other, the attaching screws engaged in the openings 8 and 9 are loosened and the brackets 7-12 are adjusted to proper position on the screws engaged in the openings 8 and the screws engaged in the openings 9 are first tightened and then the screws in the openings 8 are tightened.

The recesses 16 in the plates 13 permit swinging movement of the drapery supporting arms 21-28 without interfering with the capped ends 24.

Having thus described my invention, I claim:

1. In a window curtain and drapery fixture, a bracket having a base portion arranged to be attached to one side of a window frame and an arm extending from the base and having opposed channel portions on a face thereof, plate having a screw threaded opening therein and slidably retained on the bracket arm by the channel portions of the bracket arm to have adjustment toward and away from the base portion of the

bracket, a socket member adapted to engage and support one end of a curtain rod and having a screw threaded shank threaded in the opening in the adjustable plate to abut the arm of the bracket and secure the plate in adjusted position, and a drapery supporting rod pivotally mounted on the adjustable plate.

2. In a window curtain and drapery fixture, a bracket comprising a base portion arranged to be attached to one side of a window frame and an arm integral with and bent at a right angle from the base portion and having the opposed marginal portions folded over in spaced relation to a face of said arm to form opposed channels on said face, a plate having a screw threaded opening therein and slidably retained on the bracket arm by the channels to have adjustment toward and away from the base portion of the bracket, a socket member adapted to engage and support one end of a curtain rod and having a screw threaded shank threaded in the opening in the adjustable plate to abut the bracket arm and secure the plate in adjusted position, and a drapery supporting rod pivotally mounted on the adjustable plate.

3. In a window curtain fixture, a bracket having a base portion arranged to be attached to one end of a window frame and an arm extending from the base and having opposed channel portions on a face thereof, a plate having an opening therein and slidably retained on the bracket arm by the channel portions of the bracket arm to have adjustment toward and away from the base portion of the bracket, and a socket member adapted to engage and support one end of a curtain rod and having a shank extended through the opening in the adjustable plate to abut the bracket arm and secure the plate in adjusted position.
